GIRDER BRACE FOR OUTDOOR SIGNS

William F. Vernon, Newton, Iowa

Application January 21, 1941, Serial No. 375,243

3 Claims. (Cl. 40—145)

This invention relates to signs such as used for outdoor advertising and particularly to metal signs of this type. Even the casual observer is impressed with the fact that mounting methods for such signs are very faulty, as indicated by the bent, awry, and misshapen signs seen along the roadway. Experienced sign people recognize that the problems presented in mounting metal signs are diverse and complicated. Besides all the variable and difficult conditions encountered, there is always the problem of capable mechanics and the economic cost limits.

It is the particular object of this invention to provide a braced metal sign that can be shipped or transported in flat condition and quickly and effectively assembled and mounted by ordinary mechanics on variable sized posts to provide a rigidly secured and braced sign of low cost.

Other objects and benefits will be disclosed by the following descriptions and drawings in which:

Fig. 1 is a back perspective view of my sign supported from the rear of a square post by my truss brace.

Fig. 2 is a similar view to Fig. 1 except the sign is mounted on a round post.

Fig. 3 is a top plan view of a metal sign mounted on a round post of larger than standard diameter causing a convex face sign mounting.

Fig. 4 is a similar view to Fig. 3 except the sign is mounted on a smaller than ordinary sign post causing a concave sign mounting.

Fig. 5 is a perspective view of a double face sign employing 4 truss braces.

Now referring to the drawings I designate my truss brace by the numeral 10. It is mounted on a post 11 by securing means such as nails through holes 13. The face member of the sign 15 is attached to the post 11 by nails 16 as shown in Figs. 3 and 4 and is braced as a girder through the truss brace 10 by attachment means through the holes 12 and 14.

The parts are designed for mounting on posts of approximately 4 inches square, or 4 inches thick but by my construction I provide means whereby considerable variation in post size is permissible and still effective results are attained. In order to accomplish this it will be noted that my brace member 10 is a channel section having a substantially wide web and narrow flanges. The channel section is cut away in the center to provide a wide, flexible, flat central section and similar flat sections on the ends. The flanges of the channel 20 are cut angularly at the ends 22 and 23 in order to substantially sup-

port the back of the face member and thus effectively support it against destructive vibration. The inner ends of the flanges 24 and 25 are cut squarely at right angles to the web and when bent around either a square or round post, as illustrated, these inner corners of the legs bend inward and bite into the post to effectively secure the brace in position on the post.

This structure is very effective in providing means whereby even indifferent mechanics can securely mount my sign in position on variable size posts. The braces are shipped and transported flat and with the face section of the sign flat—this permits compact packing. The brace 10 is usually bolted to the face 15 through the holes 12 and then bent angularly outward to pass over the post. The web of the brace 10 being substantially wide effectively lines up the brace with the face member and when the mechanic prises the members apart he places the partially assembled sign around the post then supports it by nails through the holes 16 and then hammers the brace 10 securely around the post and attaches the other ends through the holes 14. Whether the post is larger or smaller than standard, as shown in Figs. 3 and 4, the corners of the legs 24 and 25 effectively bite into the post and firmly secure the whole assembly in fixed position. This method of assembly is permitted by the relatively flexible center and end sections of the brace as will readily be appreciated by consideration of the drawings.

Although I have described a preferred channel section brace, similar results may be obtained from ribbed sections with the ribs ending in abrupt or pierced thru edges adjacent the center section and tapering at the opposite ends.

When the center section of the brace is securely set around the rear of the post it is nailed into position through the holes 13 and by consideration of Figs. 3 and 4 it will be appreciated that regardless of whether the post is larger or smaller than standard the face or girder member of the sign is securely held in trussed position either straight, convex, or concave by the brace member 10.

Now referring to Fig. 5, I illustrate double face sign and show brace members 10 in staggered opposite relationship to each other supporting the double sign faces 15 and 15'. Although I provide a relatively stiff truss brace, the center section of the brace is quite thin and it will be appreciated that no difficulty is encountered in mounting the double face sign because this thin center section does not appreciably disturb the relative

relationships of the face and brace members. It will further be appreciated that I can use my girder brace on larger signs with double or triple posts and with single or double face signs.

From the foregoing description it will be appreciated that I have provided a truss braced construction for metal signs which may be mounted on posts of variable diameters either single, double or triple posts, or single or double faced signs. The construction is such that even the ordinary mechanic will effectively and securely mount the signs under variable conditions. The brace and face section being shipped in flat, compact forms, I thereby provide an effective sign easily and economically transported and mounted by ordinary mechanics.

Having thus described my invention, I now claim:

1. In a metal sign for attachment on a wooden post, a metal face section having a series of mounting holes, a single flat channel brace having mated mounting holes, the channel having a substantial broad web and short flanges, central and end thin flat sections in the channel brace, the proportion and arrangement providing means to mount the sign on a wooden post with the face section rigidly supported by the channel girder brace from the back of the post and then bent forward manually and attached to the face section with edge portions of the flanges of the channel biting into the wooden post.

2. In a metal sign for attachment on a wooden post, a metal face section having a series of mounting holes, a single flat ribbed brace having

5 mated mounting holes, the brace having a substantial broad web and short flanges, central and end thin flat sections in the brace, the proportion and arrangement providing means to mount the sign on a wooden post with the face section rigidly supported by the flanged truss brace from the back of the post and then bent forward manually and attached to the face section with the flange edge portions of the channel anchored into the wooden post.

10 3. In a metal sign for attachment on various sizes of wooden posts, a thin flexible metal face section having a series of mounting holes, a flat part-channel section brace having mating mounting holes, the channel having a relatively wide web and short flanges, a thin flat relatively flexible rectangular central section, perforations in said sections for fastening means on the post, relatively rigid channel sections extending longitudinally in both directions from said central section, including longitudinal flange portions, said flange portions ending in angular biting edges adjacent the central portion and angularly tapered edges at their opposite ends, thin flat relatively flexible end sections adjoining the rigid sections and mating perforations for the face section in the end sections, the arrangement permitting the truss brace to be shipped as a flat member and then bent manually for mounting on various sizes of posts with the metal face section bent bow-like with the angular biting edges of the truss brace flanges engaging the various sizes of wooden posts to rigidly support the face.

WILLIAM F. VERNON.
